UNITED STATES PATENT OFFICE.

EDWARD A. CROSS, OF SPRING ARBOR, MICHIGAN.

ROOF BINDING.

Application filed December 30, 1925. Serial No. 78,402.

My present invention has reference to a simple means for protecting the ends and edges of composition roofings as well as to afford a better water tight joint between the 5 roofing and the sheathing of a building.

To the attainment of the foregoing the invention consists in the improvement as hereinafter described and definitely claimed.

In the drawings:

10 Figure 1 is a top plan view illustrating the application of the improvement, parts being broken away and parts being in section.

Figure 2 is a section on the line 2—2 of

15 Figure 1.

Figure 3 is a section on the line 3—3 of Figure 1.

Figure 4 is a perspective view of one of the edge strips.

20 Figure 5 is a similar view of one of the end strips.

The sheathing of a building, in Figure 1 of the drawings, is indicated by the numeral 1. This building is covered by a composition 25 roofing 2.

As is well known in the art, composition roofings break or crack when attached to the ends and edges of a roof structure and thereafter soon decay and rot, so that a water 30 tight roof is hard to obtain.

In carrying out my invention I make use of metal members which engage the ends and the edges of the roofing 2 in a manner to permit of the said ends and edges being 35 effectively secured on the roof or sheathing and likewise afford a water tight joint between the roofing and the roof.

In Figure 5 of the drawings I have illustrated the metal member which is arranged 40 on what I have termed the ends of the roofing 2. These metal members are arranged in strips which are centrally bent upon themselves to provide flanges 3 and 4, disposed one over the other but which, before being 45 applied, have their free edges spread away from each other. The cross sectional U-shaped strips thus provided receive the ends of the roofing 2 therein, while securing means, such as the ordinary nails 5 are 50 passed through the U-shaped strips and the roofing and, of course, enter the roof.

The protective means for the edge of the roofing is illustrated in Figure 4 of the drawings. This means is also in the nature of a metal member bent upon itself to provide a lower flange 6 and an upper flange 7. The upper flange is of a greater length than the lower flange and has its outer end rounded downwardly and inwardly to provide a small bead 8. The edge of the roofing 65 is passed over the upper flange 7, around the bead 8 and between the flanges 7 and 6. The ends of the metal device above described, and which is broadly indicated by the numeral 9, are received between the flanges 3 and 4 of 65 the metal strips which are broadly indicated by the numerals 10 and the nails 5 that pass through the outer ends of the said members 10 also pass through the member 9.

From the foregoing description, when 70 read in connection with the accompanying drawings, it will be noted that I have produced a simple and effective means for protecting the ends and edges of composition roofs and for establishing a water tight joint 75 between the roofing and the roof. In addition to this it will be noted that the elements 9 have their beaded edges projecting beyond the roof so as to afford an effective 80 water-shed for the roof. Of course, other securing means may pass through the elements 9, but as such elements are forced through two layers of roofing 2, that is, the layer overlying the flange 7 and the layer received between the flanges 6 and 7, the 85 entrance of water through the openings made by the said nails will be effectively prevented.

Having described the invention, I claim:

An edging for composition roofings, comprising a metal plate, bent upon itself to provide an underlying and an overlying flange, the overlying flange being of a greater width than the underlying flange, and the outer edge thereof being rolled to 90 provide an inwardly directed bead which is spaced from the outer edge of the underlying flange a distance to permit of the insertion of the roofing between said flanges.

In testimony whereof I affix my signature.

EDWARD A. CROSS.
